UNITED STATES PATENT OFFICE.

CLARENCE W. FERGUSON, OF TROY, NEW YORK, ASSIGNOR OF ONE-HALF TO TIM & CO., OF TROY, NEW YORK, A CORPORATION OF NEW YORK, AND ONE-HALF TO C. W. FERGUSON COLLAR CO., OF TROY, NEW YORK, A CORPORATION OF NEW YORK.

COLLAR.

971,031.

Specification of Letters Patent. Patented Sept. 27, 1910.

Application filed July 8, 1908. Serial No. 442,440.

To all whom it may concern:

Be it known that I, CLARENCE W. FERGUSON, a citizen of the United States, residing at the city of Troy, in the county of Rensselaer and State of New York, have invented 5 certain new and useful Improvements in Collars, of which the following is a specification.

My invention relates to collars, and the 10 object of my invention is to provide a collar in which there shall be no obstruction to the free movement of the necktie at the back of the collar. I accomplish this object by 15 means of the construction illustrated in the accompanying drawings, in which:

Figure 1 is a perspective view of the collar. Fig. 2 is a section along the line X—X on Fig. 1.

Similar letters refer to similar parts 20 throughout the several views.

The collar, A, is provided with a standing portion, B, and a turned over portion C. The standing portion having button holes, D, D, in the ends thereof for the purpose of 25 securing the collar to the neck band of the shirt. At about midway between the ends, on the inner side (that is the side next the neckband of the shirt when in use), on the standing portion I secure a tab, E, preferably by inserting the same between two of 30 the plies, a, b, forming the standing portion, B, and secure the same therein with the same stitches that sew the lower edge of the standing portion B. The edges and top of 35 the tab, E, are loose, and in the tab is a button-hole, F, for the purpose of securing the

collar at the back to the neck-band. As thus arranged when the necktie is placed between the standing portion B and the turned over portion C of the collar it may be readily drawn to either side, for the purpose of securing a four-in-hand or other tie in position, without the obstruction which the collar button makes when it passes through the standing portion, B, as is ordinarily the case. 40

The collar, A, provided with the tab, E, can be put on much easier than the ordinary collar, because the hand of the wearer can take hold of the tab and put it over the collar button at the back of the neckband and 50 press the collar button through the button hole, F, therein much easier than he can place the collar button through the standing portion of a collar, where it is necessary ordinarily to use two hands to perform that 55 operation.

What I claim as my invention and desire to secure by Letters Patent is:

A turned down collar having an outer or turndown portion and an inner or neckband portion, an upwardly-projecting tab connected only at its lower end to the lower edge of said neckband portion and provided with a buttonhole to receive a rear collar-button, said tab except at its lower edge being free to move away from said neckband. 60

In testimony whereof I have affixed my signature in presence of two witnesses.

CLARENCE W. FERGUSON.
